US00D787116S

(12) **United States Design Patent** (10) **Patent No.:** **US D787,116 S**
Marchica et al. (45) **Date of Patent:** **** May 16, 2017**

(54) **SET OF PEEL AWAY EYELINER STENCILS**

(71) Applicants: **Paolo Marchica**, Brooklyn, NY (US);
Beth Bender, Los Angeles, CA (US)

(72) Inventors: **Paolo Marchica**, Brooklyn, NY (US);
Beth Bender, Los Angeles, CA (US)

(**) Term: **15 Years**

(21) Appl. No.: **29/572,453**

(22) Filed: **Jul. 28, 2016**

Related U.S. Application Data

(63) Continuation-in-part of application No. 29/564,195, filed on May 11, 2016, and a continuation-in-part of application No. 29/561,912, filed on Apr. 21, 2016, and a continuation-in-part of application No. 29/522,902, filed on Apr. 3, 2015, now Pat. No. Des. 765,312, and a continuation-in-part of application No. 29/522,898, filed on Apr. 3, 2015, now Pat. No. Des. 765,909, and a continuation-in-part of application No. 29/520,792, filed on Mar. 18, 2015, now Pat. No. Des. 765,311, and a continuation-in-part of application No. 29/520,791, filed on Mar. 18, 2015, now Pat. No. Des. 765,310, and a continuation-in-part of application No. 29/520,790, filed on Mar. 18, 2015, said application No. 29/564,195 is a continuation-in-part of application No. 29/507,114, filed on Oct. 23, 2014, now Pat. No. Des. 758,007, said application No. 29/520,790 is a continuation-in-part of application No. 14/243,877, filed on Apr. 2, 2014, now abandoned.

CLAIM

The ornamental design for a set of peel away eyeliner stencils, as shown and described.

DESCRIPTION

FIG. 1 is a front perspective view of a pair of peel away stencils on a wax paper sheet;

FIG. 2 is a front view thereof;

FIG. 3 is a top view thereof;

FIG. 4 is a left view thereof;

FIG. 5 is a right view thereof;

FIG. 6 is an exploded view thereof; and,

FIG. 7 is an illustration of one stencil being peeled away from the wax paper sheet and revealing the adhesive on the backside of the stencil.

The broken lines in the drawings form no part of the claimed design.

1 Claim, 4 Drawing Sheets
